UNITED STATES PATENT OFFICE.

WILLIAM E. DALE, OF WISE, VIRGINIA.

STARTING-CRANK FOR ENGINES.

1,145,294.

Specification of Letters Patent. Patented July 6, 1915.

Application filed February 9, 1915. Serial No. 7,177.

To all whom it may concern:

Be it known that I, WILLIAM E. DALE, a citizen of the United States, residing at Wise, in the county of Wise and State of Virginia, have invented new and useful Improvements in Starting-Crank for Engines, of which the following is a specification.

The invention relates to a cranking device, and more particularly to the class of starting cranks for gas or gasoline engines.

The primary object of the invention is to provide a starting crank which is of novel form, and the construction thereof prevents injury to the operator in the event of back firing of the engine.

The invention accordingly consists in the features of construction, combination and arrangement of parts hereinafter fully described and claimed, reference being had to the accompanying drawings, in which:—

Figure 1 is a top plan view of a starting crank constructed in accordance with the invention, showing the parts in normal position. Fig. 2 is a vertical longitudinal sectional view on the line 2—2 of Fig. 1. Fig. 3 is a sectional plan view showing the parts set for a cranking action. Fig. 4 is a vertical transverse sectional view on the line 4—4 of Fig. 3. Fig. 5 is a vertical transverse sectional view on the line 5—5 of Fig. 1. Fig. 6 is a sectional view on the line 6—6 of Fig. 3. Fig. 7 is a perspective view of the outer crank shaft section and parts attached.

Similar reference characters indicate corresponding parts throughout the several views in the drawings.

Referring to the drawings in detail, 1 designates a suitable frame support having bearings 2 for a pair of crank shaft sections 40 3 and 4, respectively. The shaft section 3, which may be termed the inner shaft section, is provided with a coupling head 5 of the ordinary well-known construction for engagement with a coupling head 6 mounted 45 as usual on the engine shaft 7, while the outer crank shaft section has fixed thereto a hand crank 8. The two crank shaft sections 3 and 4 extend at their proximate ends into the opposite ends of a drum or cylinder 9 which is 50 closed at its rear end by an integral head 10 having peripheral ratchet teeth 11 with which are adapted to engage a spring dog or pawl 12 pivotally mounted on the frame support for holding the drum or cylinder 55 against retrograde rotation, while permit-

ting it to have rotation in the reverse direction.

The shaft section 3 extends through the head 10 centrally thereof and carries at its inner end a coupling or clutch member 13, 60 and is held from longitudinal movement relative to the drum or cylinder 9, while permitting it to have rotary movement by means of a collar or washer 14 and retaining pin 15. The coupling or clutch member 13 is fastened to the shaft section 3 and is formed with V-shaped teeth to engage similar teeth upon a coupling or clutch member 16 which is fixed to and carried by the outer shaft section 4, and this shaft section has a 70 limited longitudinal as well as a rotary movement, said longitudinal movement being sufficient to throw the clutch member 16 into and out of engagement with the clutch member 13 when required.

The shaft section 4 extends centrally through a head 17 which is in the form of a disk for closing the front end of the drum or cylinder 9 and is fastened thereto through the medium of the screw members 18, while 80 loosely surrounding the shaft section 4 and working against the frame support is a collar or washer 19 which is held in contact therewith by a coiled expansion spring 20 which surrounds the shaft 4 and has one end 85 working against the collar 19 and its opposite end working against the hand crank 8, the spring being designed to normally hold the coupling heads 5 and 6 out of engagement with each other.

It will of course be understood that when the coupling heads 5 and 6 are out of engagement with each other the shafts 3 and 4 may be turned in unison independently of the engine shaft, and then when it is desired to crank the engine the shaft 4 is moved inwardly against the resistance of the spring 20 to bring the coupling members 5 and 6 into engagement with each other.

The head 17 is provided with a pair of 100 diametrically disposed curved or segmental slots 21 which are adapted to receive pins or projections 22 upon the clutch member 16 when the same are separated, and the teeth thereon will ride over each other so that in this event the shaft 4 is free from the shaft 3 so that either may rotate independently. Formed on the inner side of the head 17 spaced from the ends of the respective slots 21 are stop lugs 23 with which 110

are adapted to engage the pins or lugs 22 when disengaged from the slots 21 by pushing inwardly on the shaft 4, and these lugs 22 and 23 are normally held in engagement 5 with each other through the medium of the springs 24 connected to the respective coupling or clutch member 16 and the head or disk 17 so that on the turning of the hand crank 8 both shafts 3 and 4 and the drum or 10 cylinder 9 will rotate in unison, and when the coupling members 5 and 6 are engaged with each other and the hand crank 8 is turned the engine will be started.

At one end of each slot is an inturned lip 15 or ear 25 which serves to direct the pins or lugs 22 through the slots 21 when the shaft 4 is turned in a reverse direction, and thereby disengage the couplings or clutch heads 13 and 16 from each other. When the pins or lugs 22 abut the pins or lugs 23 they will be held against the inner face of the head 17 so as not to protrude through the slots, and in this position the clutch heads 13 and 16 are locked with each other.

When cranking the engine, should back fire occur, the clutch heads 13 and 16 will automatically disengage from each other as the teeth thereon will become out of mesh, but before this occurs the clutch member 30 16 will become partially rotated so that the lugs 22 thereon will register with the slots 21 so that the clutch head 16 will have a clearance to move outwardly, and likewise the shaft 4 carrying the same, and in this 35 manner the shafts 3 and 4 are freed from each other so that the engine shaft on its reverse movement will not disturb the hand crank 8 with resultant injury to the operator or person cranking the engine.

It will be seen that my invention provides a simple, reliable and efficient type of starting device which may be applied for general use, and which may be manufactured and sold at a comparatively low cost.

What is claimed is:—

1. A starting crank comprising a crank

shaft formed in two sections, coupling members on the respective sections and adapted to be connected and disconnected by relative movement of the shafts, spring means for normally holding said coupling members disconnected, means for permitting rotary movement of one section of the shaft to a limited extent, means for holding the shaft sections against accidental disconnection 50 when the coupling members are locked together, while permitting release of said shaft sections when the engine shaft turns in a retrograde direction, and means acting on one of the shaft sections for normally holding it at the limit of its limited rotary movement.

2. A starting crank comprising a frame support, a pair of shafts journaled in said support, clutch heads on the respective shafts, a drum loosely surrounding the clutch heads and having a ratchet wheel, a dog on the frame support and engaging the ratchet wheel to hold the drum from retrograde rotation, a hand crank on one of said 65 shafts, a coupling on the other shaft for locking engagement with an engine shaft, means for holding the clutch heads in positive locked engagement with each other whereby both shafts will rotate in unison in 70 one direction but permitting the separation of the clutch heads for freeing the shafts relative to each other for permitting independent reverse rotation of one of the shafts, resilient means for normally holding 75 the shaft sections in a position for the disengagement of the coupling from the engine shaft, and means for limiting the rotation of the crank carrying shaft when the clutch heads have been separated.

In testimony whereof I affix my signature in presence of two witnesses.

WILLIAM E. DALE.
